ELECTROPLATING APPARATUS

Arthur J. Donald, Milwaukee, Wis.

Application November 6, 1936, Serial No. 109,409

1 Claim. (Cl. 204—5)

The invention relates to electroplating and more particularly to an anode for use in the plating apparatus.

Heretofore in electroplating apparatus it has been customary to suspend the anodes from a conductor extending lengthwise of the tanks by means of hooks secured to the anodes and engaging over the conductor. This hooked type of connection is a frequent source of trouble in that the connection between the hook and the conductor is often imperfect and the anode, therefore, does not receive the proper amount of current for efficient plating. One of the objects of the present invention is to provide an arrangement for suspending the anodes from the overhead bar conductor which insures a positive connection therewith and in which the anodes may be readily replaced when they are used up.

A further object of the invention is to provide an anode supporting arrangement in which the anode proper may be placed below the solution line, so that it will be used up during the plating process, and the other parts furnishing current to it are protected against attack from the solution. The invention further consists in the several features hereinafter set forth and more particularly defined by claim at the conclusion hereof.

In the drawing:

Fig. 1 is a view of an electroplating apparatus embodying the invention, parts being broken away;

Fig. 2 is a detail sectional view taken on the line 2—2 of Fig. 1;

Fig. 3 is an enlarged vertical sectional view through a part of the apparatus;

Fig. 4 is an enlarged view of the upper end portion of the anode, parts being broken away and parts being shown in section.

In the drawing, the numeral 5 designates the plating tank, 6 the work holder or cathode, and 7 the anodes from which the metal is to be taken by electrolytic action and deposited upon the work carried by the work holder, the plating being carried out in the usual manner and with various types of plating solutions. The work holder 6 is shown as provided with a hook-shaped end 8 for engaging the supporting and conductor bar 9 which extends lengthwise of the tank and is supported thereon.

A series of anodes 7 are suspended from the supporting and conductor bar 10 extending lengthwise of the tank adjacent each side thereof. Each of these bars is of copper, brass, or other suitable material and is preferably provided with an insulating coating here shown in the form of

a rubber hose 11, said bar being tapped at intervals to provide threaded openings 12 to receive the threaded ends 13 of a permanent connector member 14 which may be of brass, copper, or Monel metal. If of brass or copper, this rod connector member may have a rubber coating similar to the covering 11. The lower end of this rod has a shoulder of flange 15 which may be polygonal in outline to form a head for engagement with a wrench to facilitate turning up the screw connection between said connector and the bar 10 to tightly clamp said connector to said bar. A box type wing nut 16 is slidably mounted on the member 14 and cooperates with the flange 15 to draw the end of said member into firm clamping engagement with the threaded end 17 of an anode coupling 18 when said nut is engaged with said end, this arrangement providing a union coupling connection between the parts 14 and 18. The lower end 19 of the coupling 18 is threaded to engage in a threaded bore 20 in the anode metal plate 21.

To insure centering of the parts 14 and 18, the part 14 may have a central projection 22 formed thereon to register with a centrally disposed bore 23 in the member 18 which may also have a coating 24 of rubber vulcanized thereon or otherwise suitably applied thereto.

With this construction there is a direct positive connection between the bar 10 and all of the anodes carried thereby; yet if any of the anode plates 21 become used up, they may be readily replaced by loosening up the nuts 16 of the used anodes and replacing them with new units formed by the plates 21 and the couplings 18.

As the couplings 18 are protected, they may be removed from spent anode plates and applied to new ones.

I desire it to be understood that this invention is not to be limited to any particular form or arrangement of parts except in so far as such limitations are included in the claim.

What I claim as my invention is:

In an electroplating apparatus, the combination of an anode supporting bar, a permanent anode connector comprising a rod having threaded connection at one end with said bar and a flange and centering projection at its other end, an anode member having an aperture to receive said centering projection and a surface for abutting engagement with said flange, and a nut for tightly clamping said flange against said surface,

ARTHUR J. DONALD. 55
